CHEMICAL FIRE EXTINGUISHER

Addison O. Boniface, Bronxville, N. Y.

Application July 7, 1938, Serial No. 217,929

3 Claims. (Cl. 169—32)

The invention relates to chemical fire extinguishers of the inverting type, the purpose being to improve the reliability and performance of such apparatus by simplifying and safeguarding the process of charging them; and by systematizing and controlling the acid delivery, as hereinbelow more particularly set forth.

Chemical extinguishers, as well known, require to be periodically refilled, and it is usual for the janitor, householder, or other person in charge to refill a collection of extinguishers at one and the same time. It most always occurs that in any such collection of extinguishers to be recharged there will be a variety of different makes, each differing in some one or more particulars from the others, although all may be of the same two-and-one-half gallon size, and it is not uncommon for parts of different extinguishers to become interchanged in the process of recharging, so that when they have been replaced in service their functioning is not as intended. The differences referred to are chiefly differences in dimensions of the acid bottles, the lead stopples usually used therein and the cage or mounting in which the bottle is held.

The common lead stopple has a long tapered shank intended to extend well into the bottle-neck, when the extinguisher is in its normally erect position with the head of the stopple seated on the mouth of the bottle to prevent splashing of the acid out of it when the extinguisher is being carried. When the extinguisher is inverted for use, the stopple is intended to drop away from its seat to the extent necessary to provide an annular outlet for the acid, around the stopple stem still remaining in the bottle neck, of a predetermined cross-area. The size of this outlet is important as it controls the operating characteristics of the extinguisher. A too liberal acid outlet gives rise to a too violent chemical reaction and too great an internal pressure, discharging a stream from the extinguisher which is too forceful for effective use on a fire and also of short duration, whereas a too restricted outlet may not give enough pressure to produce a fire-fighting stream. Such a condition can occur, for example when the stopple shank is too large for the bottle neck or sticks in it so that it does not fall away on inversion, or when the stopple is too long for the bottle or its cage, or the bottle too long for the cage, so that the stopple cannot fall away far enough to open up an adequate acid outlet. In many cases the size variation of the bottles, bottle necks, stopples, and bottle mounting spaces of different makes of ex-

tinguishers is so slight as to make it difficult for the person doing the refilling to observe which parts belong together, yet the effect of assembling the wrong parts may result in greatly impaired operation, or in no operation at all, the fact being that many serious failures are known to have occurred from the misassembly of the parts at the time of recharging.

According to this invention these unfortunate consequences are made impossible. The acid bottle is so constructed that it does not require the use of a fall-away stopple and so that it prevents the application of any such stopple to it. The important functions of such stopple are accomplished by other means, which also insure the proper rate of acid delivery regardless of the make of extinguisher in which it happens to be used.

A bottle according to this invention, as at present preferred, is shown in the accompanying drawing where Fig. 1 illustrates the ordinary soda-acid extinguisher to which the invention is applied, in vertical section; Fig. 2 is a larger scale section of the bottle capped for shipment; Fig. 3 a top plan of the bottle mouth, cap removed; Fig. 4 a longitudinal section at right angles to Fig. 2; Fig. 5 a detail of the partition guard removed; Fig. 6 a section of a modified form, and Fig. 7 a plan thereof.

In Fig. 1 the main receptacle marked 1, which is provided with the usual hose and nozzle 2, is intended to contain a basic solution such as soda-bicarbonate in water, or the like. It is closed by a screw cover 3, and has a bottle cage 4, of any appropriate design fixed in its neck portion to hold the acid bottle 5, all according to the usual arrangement.

The bottle may be the usual eight-ounce glass bottle intended to be half filled with the usual four ounces of sulfuric acid. It is commonly sold containing the proper amount of acid in it, in which case this bottle can be sealed for shipment by a screw cap shown at 6 in Fig. 2. This cap screws onto the bayonet lugs 7 on the outside of the bottle neck, similarly to bottles used for other purposes, and affords the advantage that it can be removed by hand when the bottle is to be installed in the extinguisher.

Within the bore of the bottle neck there is located a member marked 8 in Figs. 2 to 5 and 9 in Figs. 6 and 7, the function of which is, first, to block the bore against the possible entry of any stopple shank into it and second, to govern the acid delivery, more particularly its rate of discharge. This member, as shown, is essen-

tially a partition dividing the bore into, or otherwise producing therein, two separate passageways marked 10 and 11.

In the form of Figs. 6 and 7, in which the passages are of equal size and length, it has been noted that one of them will function as an acid outlet and the other as an inlet for gas to replace the departing acid. The gas generated at the bottle mouth, where the acid first encounters the soda, tends to rise into one or the other of these passages thereby constituting the other as the acid outlet and thereafter the acid flow is steady and at constant rate, that is, non-gulping, to the end of the discharge. Since both passageways are calibrated with reference to the chemicals used, the resulting pressure development in the extinguisher is that best suited to the discharge of an efficient liquid stream.

In Figs. 2 to 5 the partition or guard 8 is oppositely flanged at top and bottom and one or each of the flanges is provided with a calibrated notch, marked 12 and 13 respectively. These notches, which might be round holes in the member instead of notches, represent points of least cross-area for the passageways through the bottle neck and the one marked 12 is above the other when the extinguisher is inverted. This tends to establish the passage 12 instantly as the equalizing or gas inlet, because the lower part of this side of the neck serves as a collector for the first gas generated starting it upwardly into the bottle against less of a hydrostatic head therein (on account of its relative elevation) than would be encountered through the other passage. The constant rate of acid delivery, pre-determined by the calibration of the notch 13, thus begins somewhat more quickly than in the case of the other form and with corresponding benefit to the pressure curve. It will be apparent that the guard partition may be variously contoured to carry out the functions which have been above described.

The neck bore of all machine-made bottles is slightly tapered inwardly, as an incident to their manufacture, and I utilize this taper as a means of securing the partition in place, making this member of some material inert to the acid which is slightly deformable or resilient, so that when given a proper diameter and pressed into the bottle neck, preferably to a position flush with or just below the rim, it forms a virtually integral and permanent part of the bottle, not easily removable. I have used soft lead members and members made of acid-proof rubber and other materials are available and included in the invention.

With extinguishers equipped with bottles as above described, the use of a bottle in one extinguisher or another will have no effect whatever on the operation since rate of acid delivery is fixed and not affected by the form or dimensions of any cage or container structure in which the bottle is mounted. The neck of the new bottle is sufficiently short so that even if it makes a loose fit in a cage it cannot slide or

fall therein, on inversion, to such a position as to obstruct the acid discharge. In addition it will be impossible to prevent or impair such successful operation by the attempted assembly therewith of a stopple belonging to some other extinguisher and a fruitful source of extinguisher failure is thus eliminated. At the same time the rather considerable depth of the partition member suffices to prevent any escape of acid by splashing when the extinguisher is carried about or bumped.

It is no objection to the acid bottle herein disclosed that the surrounding air within the main container of the extinguisher has access to the sulfuric acid through the calibrated openings in the bottle neck and that it therefore may invite dilution of the acid by gradual absorption of water vapor from the air. I find that such absorption proceeds at a very slow pace and that it is no more perceptible with this new bottle than with the prior bottles covered by the conventional fall-away lead stopple, such stopples rarely, if ever, producing the hermetic closure necessary to prevent all moisture absorption. However, complete isolation of the acid from contact with air can be easily produced, whenever that is deemed advisable under special conditions, by floating a thin film of mineral oil on the acid, or on the basic solution in the main container, preferably the former. Such a film avoids all absorption and does not impair the operation.

This application is a continuation in part of my prior and copending application filed September 20, 1935, Serial No. 41,350.

I claim:

1. An extinguisher acid bottle adapted to be inverted for discharge having a combined guard and flow-regulating member permanently supported inside of its neck opening and shaped to provide two passageways, one of said passageways having a point of least cross-area located near the upper side of said member when the bottle is inverted to form a downwardly open gas-collecting chamber directly below said point of least cross-area.

2. An extinguisher acid bottle adapted to be discharged by inversion having a flow-regulating member located inside of its neck opening shaped to form two passages through the neck each having a point of least cross-area, and said points of least area being at different vertical levels when the bottle is in inverted position.

3. A soda-acid fire extinguisher comprising a receptacle adapted to contain a soda-bicarbonate solution, an acid bottle secured in position adjacent the upper end of the receptacle, said bottle having a vertical partition permanently fixed within its neck opening to provide a plurality of passageways within the neck opening, said vertical partition being substantially contained within the neck opening, whereby the partition acts to prevent the insertion of a normal acid bottle stopple within the neck opening.

ADDISON O. BONIFACE.
